US0D1065045S

(12) **United States Design Patent** (10) **Patent No.:** **US D1,065,045 S**
(45) **Date of Patent:** **** Mar. 4, 2025**

(54) **MOBILE POWER BANK**

(71) Applicant: **Shenzhen Utopia-Originality Technology Co., Ltd**, Shenzhen (CN)

(72) Inventor: **Hongyuan Lu**, Shenzhen (CN)

(73) Assignee: **Shenzhen Utopia-Originality Technology Co., Ltd**, Shenzhen (CN)

(**) Term: **15 Years**

(21) Appl. No.: **29/853,138**

(22) Filed: **Sep. 13, 2022**

(30) **Foreign Application Priority Data**

May 18, 2022 (CN) 202230293685.9

(51) **LOC (15) Cl.** **13-02**

(52) **U.S. Cl.**

USPC **D13/103**; D13/107

(58) **Field of Classification Search**

USPC D13/101, 103, 104, 107, 108, 110, 112, D13/113, 114, 118, 119, 122
CPC .. (57) **CLAIM**

The ornamental design for a mobile power bank, as shown and described.

DESCRIPTION

FIG. 1 is a front, left and top perspective view of a mobile power bank, showing my new design;

FIG. 2 is a front, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
